PORTABLE WHEEL SPINNER UNIT

Lee Hunter, Rte. 1, Box 136, Creve Couer, Mo.

Filed Sept. 12, 1958, Ser. No. 52,620

Term of patent 14 years

(Cl. D55—1)

FIG.1

FIG.2

FIG.3

Fig. 1 is a perspective view of a portable wheel spinning unit showing my new design;

Fig. 2 is a plan view of said unit, and

Fig. 3 is a side elevational view of said unit, the opposite side being similar.

I claim:

The ornamental design for a portable wheel spinning unit, as shown and described.
